HENRI CHIREIX, OF PARIS, FRANCE

VACUUM-TUBE GENERATOR SYSTEM

Application filed November 6, 1926, Serial No. 146,620, and in France November 25, 1925.

The present invention relates to vacuum tube generator systems and more particularly to oscillator arrangements particularly adapted to extra short waves.

5 In my copending application, Vacuum tube generator system, Serial Number 99,740, filed April 5, 1926, I have disclosed several circuit arrangements, which by a convenient distribution of the radio frequency potentials to ground, allow of considerably diminishing the losses, as well as the stray capacitance.

10 It is an object of the present invention to provide an arrangement particularly adapted to extra short waves, and in which all of the massive and large apparatus are grouped in such a manner that they will all be, from a radio frequency viewpoint, at practically zero potential to ground. In this manner, as set forth in my copending application mentioned above, the capacitance to ground of these parts does not interfere, while the circuit losses are reduced to a minimum.

15 The novel features characteristic of my invention are set forth with particularity in the appended claims. The invention itself, however, both as to its construction and mode of operation together with the objects and advantages thereof will best be understood by 20 reference to the following description taken in connection with the accompanying drawing, in which

25 Figure 1 shows schematically the chief features of the invention,

30 Figure 1A shows a modified arrangement for obtaining longer waves,

35 Figure 1B shows another modified arrangement for obtaining still shorter waves,

40 Figure 2 illustrates diagrammatically the arrangement of the self-inductance,

45 Figure 3 is a modified construction of the grid connection shown in Figure 1,

Figure 4 shows a symmetrical arrangement that may be used employing two triodes.

50 Referring to the arrangement shown in Figure 1, elements 10, 11 and 12, respectively, stand for the filament, the grid, and the plate of the wave-generating triode 13. 1 and 2 denote the high and low potential sources 55 which are required for feeding the plate 12

and for heating the filament 10 and which are conventionally represented as a direct current generator and as a battery, respectively, said sources having a common point that is grounded. 3 is the ammeter measuring the plate output; 4 is the customary stopping condenser; 5 and 6 stand for the grid resistance (leak) and the usual grid condenser adapted to negatively polarize the grid; 7 denotes the D. C. ammeter measuring the 60 D. C. rectified by the grid; 8 is a high frequency ammeter, while 9 represents the self-inductance unit for maintaining oscillations. This self-inductance unit is in reality made up of 3 windings *a*, *b* and *c* strongly coupled 65 with one another, and they are preferably given the form of helices, it being merely for the sake of clearness of representation that the same is here illustrated in developed form.

70 Since the circuit arrangements here involved are specially intended for short-wave work, no other capacities than such internal capacities of the triode as exist between electrodes 10-11, 11-12 and 10-12, are employed, although it will be understood that a capacity 14 could be inserted as shown in Fig. 1A in order to obtain longer waves. The main paths of the radio frequency currents are along 12-4-6-8-11-12 and 80 along 12-4-6-8-9-10-12. It will be noted that, provided condensers 4 and 6 are sufficiently large compared with the internal capacity of the tube (plus capacity 14, if desired), the radio frequency potentials set up 85 across condensers 4 and 6 will be negligibly low so that from a radio frequency viewpoint, all of the elements 12, 3, 4, 5, 6, 7, 8 are at a potential coming very close to that of the ground. It will be noted, moreover, that 90 the radio frequency potential between grid and filament is governed by the potential fall along the connection 16 to the grid 11 plus the drop of potential due to magnetic stray 95 existent between the three windings of the triple self-inductance. Arrangements are preferably so made that the losses (leakage) turn out to be very small by building the self-inductance unit 9 in a manner as diagrammatically indicated in Fig. 2, which 100

shows in central vertical section a helical coil structure embodying the wires *a*, *b* and *c*. In this manner, very strong coupling is obtained between the different windings. Another desirable plan is to place the assembly inside a metallic cage so as to prevent it from radiating energy through the room where it is mounted.

It will furthermore be readily understood that the condenser 14 disclosed in Fig. 1A could be replaced by a self-inductance coil 15, shown in Fig. 1B. The mounting of this self-inductance coil would further permit of diminishing the wave-length. In this latter case, a recommendable plan would be to extend the self-inductance coil 9 beyond the point brought to the grid 11 as indicated in Fig. 3, and to bring the end to the ammeter 8. The part of the winding located above point 16 would then represent the self-inductance coil 15 of Fig. 1B. This scheme, among other things, offers the advantage that the system radiates far less energy on account of the fact that the fluxes in the two parts of the self-inductance coil 9 tend to work in opposition.

Fig. 4 illustrates a modification of the circuit arrangement Fig. 1 in which the arrangement is made symmetrical by the provision of two triodes 13 and 13'. Also this scheme comprises plate and filament sources 1 and 2, respectively, with a common point connected with earth, stopping condenser 4, grid leak resistance 5 and condenser 6, and coupled inductances 9 and 9' which unite, respectively, the filaments 10 and 10' and the grids 11 and 11'. The self-inductance coils always constitute but one and the same self-inductance unit as disclosed in Fig. 2, and all of the elements other than the oscillation coil are practically at ground potential from a radio frequency viewpoint. Particularly in the case of tubes provided with water circulation the water supply conduit for the plates have no radio frequency potential. This arrangement like the one shown in Fig. 1 insures a minimum amount of losses, while moreover it affords the location of instantaneous potential points that are in opposition for the excitation of symmetric antennae.

Having thus described my invention, I claim:

1. In a circuit arrangement particularly adapted to the generation of very short waves, the combination with a three-electrode vacuum tube, of an oscillation circuit comprising the inter-electrode capacity between plate and grid electrodes of said tube, an inductance in the grid circuit, an inductance in each of the leads of the filament heating circuit, said inductances being closely coupled, a filament heating source, a plate supply source, a common ground connection for both said sources, and a grid leak resistance and shunt condenser connected between the grid

inductance and said common ground connection.

2. A circuit arrangement particularly adapted to the generation of very short waves, comprising a vacuum tube having the usual filament, grid and plate electrodes, an inductance in each of the filament leads, a source of energy arranged to heat the filament through said inductances and having one of its terminals grounded, an inductance connected to the grid electrode and closely coupled to said first mentioned inductances, a grid leak resistance connected between the grid inductance and heating battery ground, a high voltage supply source connected between plate and ground, and a pair of large-capacity condensers, one shunting the plate supply source and providing a direct path for high frequency currents between plate and ground and the other shunting the grid leak resistance.

3. In a system for generating high frequency currents, a pair of symmetrically arranged vacuum tubes, the plates thereof being connected together and the filaments thereof fed in parallel, an inductance in each of the leads to the filaments, a common source of energy for heating said filaments through said inductances, said source being grounded at one terminal, a common inductance connected to both grids and coupled to said first mentioned inductances, and a common source of energy connected to both plates of the tubes and also grounded at one terminal.

4. In a system for generating high frequency currents, a pair of symmetrically arranged vacuum tubes having their anodes connected together and their filaments fed in parallel, an inductance in each of the leads to the filaments, a common source of energy for heating said filaments through said inductances, said source being grounded at one terminal, a common inductance connected to both grids and coupled to said first mentioned inductances, a common source of energy connected to both plates of the tubes and also grounded at one terminal, and a grid leak resistance and shunt condenser connected between the midpoint of the grid inductance and the ground connection between the inductances in corresponding leads to the filaments.

HENRI CHIREIX.
